United States Patent Office

Des. 224,731
Patented Sept. 12, 1972

224,731

BOTTLE

Le Roy B. Nathan, 1446 Ashbel Ave.,
Berkeley, Ill. 60163

Filed Nov. 24, 1970, Ser. No. 26,143

Term of patent 14 years

Int. Cl. D9—01

U.S. Cl. D9—23

FIG. 1 is an elevational view of a bottle showing my new design;

FIG. 2 is a top plan view; and

FIG. 3 is a bottom plan view thereof.

The drawing is stippled to show contrasting color.

I claim:

The ornamental design for a bottle, as shown and described.
